US00D962300S

(12) **United States Design Patent** (10) **Patent No.:** **US D962,300 S**
(45) **Date of Patent:** **** Aug. 30, 2022**

(54) **COOLER**

(71) Applicant: **LIFETIME PRODUCTS, INC.**,
Clearfield, UT (US)

(72) Inventors: **Allen Keetch**, South Weber, UT (US);
Robert A. Astle, Farmington, UT (US)

(73) Assignee: **LIFETIME PRODUCTS, INC.**,
Clearfield, UT (US)

(**) Term: **15 Years**

(21) Appl. No.: **29/730,693**

(22) Filed: **Apr. 7, 2020**

(51) LOC (13) Cl. **15-07**

(52) U.S. Cl.

(57) **CLAIM**

The ornamental design for a cooler, as shown and described.

DESCRIPTION

FIG. 1 is a top perspective view of a first embodiment of our new design for a cooler;

FIG. 2 is a bottom perspective view thereof;

FIG. 3 is a front elevation view thereof;

FIG. 4 is a rear elevation view thereof;

FIG. 5 is a left-side elevation view thereof;

FIG. 6 is a right-side elevation view thereof;

FIG. 7 is a top plan view thereof;

FIG. 8 is a bottom plan view thereof;

FIG. 9 is a top perspective view of a second embodiment of our new design for a cooler;

FIG. 10 is a bottom perspective view thereof;

FIG. 11 is a front elevation view thereof;

FIG. 12 is a rear elevation view thereof;

FIG. 13 is a left-side elevation view thereof;

FIG. 14 is a right-side elevation view thereof;

FIG. 15 is a top plan view thereof; and,

FIG. 16 is a bottom plan view thereof.

The portions of the cooler shown in broken lines form no part of the claimed design.

1 Claim, 14 Drawing Sheets
